UNITED STATES PATENT OFFICE.

CHARLES WILSON LEISER, OF SALT LAKE CITY, UTAH.

TELEGRAPH-TRANSMITTER.

No. 853,556.

Specification of Letters Patent.

Patented May 14, 1907.

Application filed February 15, 1906. Serial No. 301,165.

To all whom it may concern:

Be it known that I, CHARLES WILSON LEISER, a citizen of the United States, residing at Salt Lake City, in the county of Salt Lake and State of Utah, have invented new and useful Improvements in Telegraph-Transmitters, of which the following is a specification.

As telegraph transmitters are now constructed, they are unable to transmit Morse signals over long distance telegraph circuits, because the lever which makes the dots to be transmitted is opposed by a system of contacts which stops the lever in its forward movement; thereby causing it to recede more quickly than if these causes were removed. This premature stoppage produces a short, quick contact, which will not carry on a long distance circuit. My invention removes this difficulty. Again, on all direct contact points an oxid forms, which prevents an electric contact until the points are cleaned.

In this improvement the contacts are effected by a sliding movement in which the points or surfaces of contact overlap, and so overcome the difficulties above mentioned. That is, it prevents the formation of oxid on the contacts, and insures either a long or short contact as required to meet the conditions of long and short circuits.

As another feature of my transmitter I employ a flexible armature lever, which costs less because it has fewer parts than the ordinary form. There are no bearings to wear out the adjustment cannot change after being set and it is capable of the greatest speed.

The accompanying drawing illustrates the invention, its various parts being referred to by letters, similar letters denoting corresponding parts in the several views.

Figure 1 is a side elevation of the device, partly in section. Fig. 2 is a plan view and showing the connections. Fig. 3 is a modification of the sliding contact surfaces; and Fig. 4 is an elevation of the post E partly broken away on line x-x of Fig. 1.

The letter A designates an electro-magnet mounted in the usual way.

B is a stationary post, and C is a flexible armature lever, rigidly, but adjustably held in the post B. It passes through an opening a in the magnet support A'. This lever is formed of the part c, held in the post B, a flat spring portion c' and an outer portion c'' which oscillates laterally as shown by dotted lines.

D is the armature piece on lever C, which

also carries a weight W and a spring contact piece d.

E is a permanent post carrying a loose weight e, and so placed that when lever C is at rest, it presses slightly against the weight e, whose function is to prevent vibration of lever C, when released by magnet A.

f and g are operating keys provided with retractile springs f', g'. 65

H is a battery.

The parts I and i constitute a circuit break contact; I being fastened to lever C, and i being adjustably attached to post J. Key f is adapted to contact with point v, and key g with point w. 70

K is a post, holding an adjustable bar L, to which is connected, flexibly, the convex contact O; and m is a corresponding flexible, convex contact secured to oscillating lever C. 75 These two convex faces have a mutual, sliding, or lapping contact.

n, n' are binding posts leading to the telegraphic circuit to be worked.

In operating this transmitter when key f is made to contact with point v, a circuit is established through wire 3, battery H, wire 4, magnets A, wire 2, circuit break contacts I, i and wire 1 back to point v. This causes the magnets to attract the armature D and moves forward the lever C. This contact faces O and m, which shunts binding posts n, n' through the parts Q, L, O, m. This shunting n, n', would cause the telegraph circuit to be closed; and owing to the circuit break contacts at I, i, the contact of O and m would be only momentary; the circuit break contacts giving an oscillating movement to the lever C, which would cause a series of opening and closing movements at O, m so long as key f is kept closed, and so transmitting dots to the telegraph circuit at n, n'. 80

When key g is made to contact with w a circuit is established through parts 5, 6, Q, Q' to posts n, n', necessarily closing the circuit connected with n, n'; and there being no circuit break in this circuit, the circuit will remain closed so long as key g is in contact with point w. By the proper period of time in this contact, dashes are sent to the telegraph circuit to be worked. It should be noticed that the dashes are transmitted through the parts mentioned irrespective of the other parts of the machine. In other machines the dashes as well as the dots are made by a lever actuated by magnets. 100 105 110

In my double key system, when dots fol-

low a dash, press both keys the proper length of time for the dash, then release the dash side and the dots will follow. If a dash follow a series of dots, gently close the dash side and the dash will follow closely on the dots. All this is done without the usual "wabble" of the whole hand.

What I claim and desire to secure is—

1. The combination with an electric battery of a flexible lever, an armature on said lever, sliding spring contacts, electro-magnets to operate said lever, a vibration arrester comprising a support having a vertical recess therein, a cross pin in said recess and a ring hung loosely on said pin, a circuit break, a pair of operating keys and suitable connections between the parts, as herein set forth.
2. In a telegraph transmitter having an electric battery, a flexible lever operated by electro-magnets, an armature on said lever and sliding spring contacts, a vibration arrester formed of a support having a vertical

recess, a cross pin in said recess and a ring loosely hung on said cross pin, a circuit break, a pair of operating keys and suitable connections as herein described.

3. The herein described vibration arrester comprising a support having a vertical recess in its upper end, a cross pin in said recess and a ring suspended loosely on said pin and adapted to receive the impact of the vibrating object.

4. In an electric machine a post having a recess in its upper end, a ring having an inner elastic surface, a cross pin in said recess on which said ring is movably supported so as to yieldingly receive the impact of a vibrating lever, as herein set forth.

In testimony whereof I affix my signature, in presence of two subscribing witnesses.

CHARLES WILSON LEISER.
